The ornamental design for a magnetic hat headband, as shown and described.

DESCRIPTION

FIG. 1 is a perspective view of a magnetic hat headband; FIG. 2 is a front elevational view thereof; FIG. 3 is a rear elevational view thereof; FIG. 4 is a right side elevational view thereof, a left side elevational view being a mirror image thereof; FIG. 5 is a top plan view thereof; FIG. 6 is a bottom plan view thereof; FIG. 7 is a top plan view thereof, showing the plane upon which a cross-sectional view is taken and shown in FIG. 8; FIG. 8 is a cross-sectional view thereof, taken along line 8-8 in FIG. 7. FIG. 9 is a perspective view of a magnetic hat headband, wherein the magnetic hat headband is integrated with a baseball style cap and used to secure a pair of glasses to the cap; FIG. 10 is a right side elevational view thereof; and, FIG. 11 is a rear elevational view thereof. The broken line showing of glasses and a hat brim and top is included for the purpose of illustrating environmental structure and forms no part of the claimed design.
